UNITED STATES PATENT OFFICE.

LESLIE R. BRUNDAGE, OF CHICAGO, ILLINOIS.

APPARATUS FOR COMPRESSING AND ASSEMBLING COIL SPRINGS.

Application filed December 5, 1924. Serial No. 754,159.

To all whom it may concern:

Be it known that I, LESLIE R. BRUNDAGE, a citizen of the United States, and a resident of Chicago, in the county of Cook and State of Illinois, have invented certain new and useful Improvements in Apparatus for Compressing and Assembling Coil Springs, of which invention the following is a specification.

- 10 In the manufacture of mattresses, seatings and cushions of various kinds metal coil springs have come to be used in place of the heavy, more expensive, and less sanitary pads of felt and the like, the springs 15 being covered with relatively thin padding. To insure evenness in the spring expansion, that is, to produce a suitably uniform surface over the whole series of spring units, and to guard against displacement, each of 20 the coils is compressed and inserted in a separate pocket, in a strip made of muslin or the like, containing a series of these "pockets." These strips are then joined together to make up the desired area of 25 compressible surface for the mattress or article being manufactured. The material of which the "pockets" are made allows the coil springs within same to be compressed in use, but provides a uniform limit against 30 excessive expansion or displacement.

Heretofore in this manufacturing business the individual springs after being formed, cut off and dropped from the coiling machines, have been put through the further 35 assembling operation by rather necessarily slow hand labor. The coils are passed onto a table, where they frequently become badly tangled and mixed up, and require separation. Then the operator compresses each 40 one and inserts it in the "pocket". Very often the coil will fly out of the operators' hands. As the coiling machine generally forms and cuts off the completed coils at the 45 rate of about 45 per minute, it has been necessary to provide a number of operators to perform the further hand operations to keep up with the coiler. Even when the operators become experienced and skilled, it usually 50 requires about six girls to do this work besides the operator at the coiling machine.

The object of my invention is to simplify and improve these manufacturing operations and to very considerably reduce costs by speeding up the assembling and employing 55 much less labor. I accomplish these results by providing the herein described appara-

tus, which is simple, light and low in cost to construct and operate, to do what now requires so much more hand labor.

Referring to the drawings, forming a part 60 of this specification, and in which like letters of reference refer to similar parts in the several figures, Fig. 1 is a top plan view; Fig. 2 is a vertical sectional view taken on the line 2-2 of Fig. 1; Fig. 3 is a detail 65 view of one of the guides for adjusting the spindle opening through which the springs are fed according to different dimensions of coils. And Fig. 4 is a more enlarged detail 70 sectional view of the "spindle" end of the 75 apparatus.

In the drawings a^1 indicates any suitable table top, a^2 marks the side frames and a^3 the legs. The table frame also serves to support the shafts b^1 of the conveying mechanism. b^2 , b^3 and b^4 are suitable gears, over which travels a suitable conveyor chain c^1 ; and c^2 marks a power driving means for driving the conveyor.

Spaced apart on the conveyor chain c^1 80 there is mounted a series of pegs, which are here marked separately from d^1 to d^{11} .

Mounted on one end of the table is what I term the inclined compressing guide and feeding spout. The guide is preferably 85 made in two similar halves, positioned on opposite sides of the line of travel of the conveyor pegs. The inclined guides are marked respectively, e^1 and e^2 . The lower or outer end is marked e^3 and e^4 . This portion of the respective guide members and the inclined end may be made in one integral metal strip, or in separate pieces, as desired. These outer guide ends e^3 and e^4 are spaced 90 apart from the table top, or extension therefrom, as well as spaced from each other, to form the spout or opening e^5 , through which the compressed spring coils are fed forward to the strip pockets. The spacing distance is regulated according to the size of the coils and extent to which the coils are to be compressed.

The springs s are taken from the "coiler," or machine on which they are formed from the wire, as that machine cuts off the formed spring. There are various coilers in use, but none of the details thereof are here shown. My new assembling apparatus is preferably timed to operate at the same speed as the coiler, usually about 45 per minute; and it may be so connected that the formed springs drop from the coiler to the first conveyor 100 105 110

- peg. However, the coiler has to be watched to keep same properly operating and there may be some springs cut off which for one reason or another are defective and should not be used. It is preferable, therefore, to have the coiler boy take each spring as it is cut off and drop same over the conveyor peg, throwing aside any spring which is defective.
- 10 The coiler forms the spring wire into the desired dimension of coil, and as they come from the coiler same can spring to their fully extended size. In Fig. 2 an extended spring *s* is shown dropped loosely over the first peg *d*¹. As the conveyor *c*¹ carries the pegs forward the pegs pass in the open top channel formed by the spacing between the guides *e*¹ and *e*². This space is sufficient to allow the pegs to travel freely but is less than the dimension of the spring coils. When the pegs move forward the inclined guides *e*¹ and *e*² gradually compress the springs carried by the pegs. In Fig. 2 the spring on peg *d*³ is shown as just starting to be compressed. As its peg moves forward the inclined guides gradually increase the compression. When moved forward to the position of peg *d*⁴ the coil is partly compressed, and at the bottom of the incline it is fully compressed. Here the compressed coil is passed into what I call the spout *e*⁵, and from the spout they are fed into the pockets, which are held over the open end of the spout.
- 35 As the springs are moved forward into the spout *e*⁵ the respective conveying peg is withdrawn from the inside of the coil. This may be accomplished by arranging the conveyor *c*¹ for travel over gears as shown in Fig. 2, where between the gears *b*⁸ and *b*⁴ the conveyor moves in a straight line. The shaft carrying the gear *b*², however, is positioned at a lower level, and the conveyor chain *c*¹ in traveling from the idling gear *b*⁴ to the gear *b*² is on a suitable incline which gradually lowers and ultimately brings the pegs below the line of the table top and withdraws the peg from the coil. The peg *d*⁵ is shown nearly withdrawn, while peg *d*⁶ is fully withdrawn and will pass under the table, advancing to the position shown by the pegs *d*⁷ to *d*¹¹ and around again to the position *d*¹.
- 50 As the springs enter the spout *e*⁵ and are fully compressed and their carrying pegs withdrawn the compressed coils touch each other as shown and the entering coil pushes or feeds the others ahead and out the end of the spout *e*⁵. The operator holds the pocket, having an opening into which the spring is inserted, over the end of the spout, and then the springs are free to again expand, but only to the extent allowed by the size of the pocket. These so-called pockets are usually made of muslin or like material
- and generally sewed in strips. In Fig. 1, the dotted outline *f*¹, *f*², *f*³ and *f*⁴ marks a series of pockets in such a strip, the open end of the pocket *f*¹ being slipped over the spout end and ready to receive a spring coil. 70
- The two sides of the compressing guides *e*¹ *e*² may be fastened to the table by screws, as indicated in Fig. 1. Where the channel through which the springs are fed forward on the pegs approaches the spout end, I 75 prefer to provide an additional adjustable guide piece on each side. These are here marked *e*⁶ and *e*⁷. Fig. 3 is a separate detail view of one of these adjustable guide pieces. These may have two slots as shown, in which set screws pass to fasten the piece to the table, the slots permitting the guide pieces to be moved for adjustment of distance between the guides according to the different dimension coil being run, and then the 80 guides are fastened.
- To protect the operator from the traveling pegs any suitable shield or guard, marked *h* may be provided.
- 85 Various changes may be made in the construction without departing from the spirit and scope of the invention. For example, while I prefer the sprocket gear and chain conveyor, I also contemplate the use of suitable rollers and belt conveyor. 90
- Having described the invention, what I claim as new and desire to secure by Letters Patent is the following.
- Claims:
1. An apparatus of the character described comprising a plurality of pegs for carrying the coil springs, a conveyor on which the pegs are mounted, a supporting member, means for driving the conveyor, an inclined guide for compressing the spring coils while same are being moved forward on the pegs, a spout into which the compressed coils are forced for feeding into the spring containing pockets, and the conveyor so arranged in the line of travel that the pegs carried thereby are withdrawn after the spring coils are compressed and passed into the spout. 100
- 105
2. A machine for the purpose described comprising in combination a supporting member, conveying mechanism mounted in said supporting member, means for driving said conveyor mechanism, a series of pegs spaced apart and traveling with the conveyor for carrying the spring coils, guide members in the line of travel adapted to compress the coils as same move forward on the pegs, a discharge end into which the coils are passed after compression and the pegs withdrawn therefrom, the said discharge end arranged to hold the coils under compression while therein and having an opening through which the coils are fed into the receiving pockets. 110
- 115
3. A machine for the purpose described 120
- 125
- 130

comprising in combination a series of pegs for carrying the coil springs, a conveyor chain on which the pegs are secured, a supporting frame and means for mounting the conveyor mechanism thereupon, means for driving the conveyor mechanism, an inclined guide member at the side of the pegs arranged to compress the spring coils as same are moved forward on the traveling pegs, a 10 spout tube into which the compressed coils are forced and then fed into the spring containing pockets when held over the open outer end of the spout tube, and the conveyor so arranged that the coils are freed from 15 the pegs after entering the feed spout substantially as set forth.

series of pegs spaced apart on and traveling with the conveyor for carrying the spring coils, an inclined member on each side of the line of travel spaced apart to 25 permit the pegs to travel but extending over and adapted to compress the coil springs gradually as same move forward under the inclined members, a discharge end into which the coils are forced after being compressed and the pegs withdrawn therefrom, 30 adjustable means for regulating the passage to the discharge end according to variation in size of coils, the discharge end being arranged to retain the coils under compression and having an opening through which the coils are fed into the receiving pockets, 35 substantially as set forth.

4. A machine for the purpose described comprising in combination a supporting frame, a traveling conveyor mechanism 20 mounted in said supporting frame, means for driving said conveyor mechanism, a

In testimony whereof I have hereunto signed my name to this specification.

LESLIE R. BRUNDAGE.
